UNITED STATES PATENT OFFICE.

BENJAMIN FRANKLIN WRIGHT, OF ELK HILL, VIRGINIA.

MARINE VESSEL.

Application filed March 3, 1924. Serial No. 696,576.

To all whom it may concern:

Be it known that I, BENJAMIN F. WRIGHT, a citizen of the United States of America, and a resident of Elk Hill, county of Goochland, and State of Virginia, have invented certain new and useful Improvements in Marine Vessels, of which the following is a full and clear specification.

My invention relates to the propulsion of all classes of vessels, driven either by steam, electrical mechanism, internal combustion engines or any other applied power which may be used for driving any class of screw or spiral propellers, and it has for its objects to secure an increase of speed and economy of operation. There are other advantages which necessarily follow, but greater speed and the avoidance of lost power are the immediate and special objects of my proposed improvements.

I accomplish this in the following manner, as shown by the accompanying drawings, in which—

Fig. 1 is a side elevation of the hull of a vessel, the bow portion of which is shown in section;

Fig. 2 is a cross-sectional view taken on the line 2—2 of Fig. 1;

Fig. 3 is a view similar to Fig. 2, taken on the line 3—3 of Fig. 1;

Fig. 4 is a view similar to Fig. 2, taken on the line 4—4 of Fig. 1;

Figs. 5 and 6 are detail cross-sections showing modified forms of hulls having double propulsion means;

Fig. 7 is a detail view showing a further modified form; and

Fig. 8 is a view in side elevation of a hull showing diagrammatically one of the old forms of vessel propulsion.

A tube-like casing, extending the full width of the vessel and enclosing a shaft 4, carrying one or more propellers 2 and 3, is provided at the bow of the vessel. Suitable bearings 5 and 6 for shaft 4 are provided in an upper fore-castle room J, and at its lower end the shaft is supported on a bearing 7. This lower bearing 7 is supported by opposite sides of casing 1 by arms whose sides stand parallel with the propeller shaft, with its edges only confronting the current of water passing through the casing.

The propeller blades should have a varying pitch on their faces, increasing from their front or cutting edges back to their op-

posite edges where the water finally leaves them, so that water may be taken easily and without shock and impinge as equally as possible on all parts of the blades. This would help to prevent a whirling motion of the water, thereby making propellers more effective.

While no claim is made to any special form or style of propellers, there are certain features which may be used which are necessary to obtain the best results. The faces of all blades should incline slightly forward so as to throw water towards the shaft by drawing it away from the walls of the casing and the bottom of the bow of the vessel, as indicated by arrow lines in Fig. 1; also in diagram Fig. 7, in which a continuous screw or spiral 8 is represented. In these figures, the space between the lines of the arrows represents the course of the water current created by the propeller, the water being drawn in from the walls of the casing and the bow of the vessel. The inclining forward of the propeller blades, it is thought, might be of some advantage in this special device, but is not an absolute necessity because propellers of ordinary form will also act.

If a continuous screw is used, as shown in Fig. 7, its pitch ratio should preferably steadily increase from its upper to its lower end; and its screw should be at least a double screw rather than a single-thread screw; that is, two or more such vanes should wind around and be secured to the shaft and their pitch ratio continue appropriately to increase to their end. What the proper ratio of pitch increase would be will always depend on a variety of circumstances and must be left largely to the judgment and experience of the vessel's designer; this has proven best with propellers of all classes.

If a propeller or a system of propellers having two or more blades is used, as indicated in Fig. 1, the pitch of each succeeding propeller should increase, but their diameters, as shown, may decrease to advantage. The same is true of spiral vanes represented around the shaft in diagram, Fig. 7. It will be noticed that the propeller-shaft is placed at an angle to a line parallel with the ship's greatest length. As shown in Figs. 1 and 7, that angle happens to be 30 degrees, counting from a true level.

It is believed that an angle of 30 degrees,

or at least near that angle, will be found best for best results. At this angle, it appears best for throwing a swell of current back under the vessel so as to fill in its wake and give a lifting effect to the stern, and at the same time the propellers will have a decided tendency to lift the vessel in front from the direct action of the engines, thus not only meeting swells, but also causing the vessel to ride higher in the water, thereby avoiding a proportion of the resistance in front; also this angle gives two-thirds of the engine-driving-power for a forward pull, its other third being devoted to an upward pull; and, thirdly, it makes the ship glide more smoothly and prevents plunging so deep into the ocean swells. Lastly, this angle gives sufficient force from the engines to hold the vessel steady or from careening; yet such force is in no way taken from the actual forward and upward pulling power; that is, if 1500 H. P. were applied, 500 H. P. would be given to holding the vessel steady in an upright position, yet this same force would not be taken from the lifting power of the engine any more than the pulling on a rope and thus keeping it taut detracts from the power applied to an object at its other end. On the contrary, it adds to the ease of propulsion by holding the vessel more steady from rolling.

Suitable power is applied to shaft 4 in room J, somewhere between bearings 5 and 6, as indicated by *p*. No form of any special connections with the driving power can properly be given here, because such connection must depend on the kind of engine used; also it may in some cases depend on the construction of the ship's hull. It may be connected with the driving power by a crank, toothed gearing, worm gearing, or otherwise—the various ways in which this may be done forms no part of my invention.

So far, but one system of propellers, secured on a single shaft, has been referred to. I will now describe my invention as it relates to a double system of propellers, as shown in Figs. 5 and 6; that is, where two or more shafts are used, each carrying one or more propellers. The manner in which this is effected is identical with that of a single shaft, being but a duplicate of same and therefore needing no further description. The only change is in the casing enclosing the different systems.

Referring to Fig. 5, right-hand and left-hand propellers are shown, which are adapted to rotate toward each other, as indicated by the arrows. Where parallel screws are used, the diameter of the screws, of course, would not be the same as though only one was used, neither would their pitch and number of revolutions be the same; their pitch would either be of a higher ratio, or their revolutions greater to secure the same

speed for the vessel. The object sought in such case is to construct a large vessel and yet one not carrying extra large propellers. A second object is that, by using parallel propellers, the vessel can be given a quicker and shorter turn, as these propellers may be driven by engines independent of each other and either one may be reversed, giving a backward effect, while the one on the opposite shaft pulls forward. A further object for using parallel propellers is to enable a vessel to be constructed with an unusually shallow draught and broad beam. The object sought in this instance is not to reduce the size of the propellers, but to secure the shallow draught, shown in Figs. 5 and 6.

Casing 1 practically forms the bow, or a percentage of the bow of the vessel as adapted to my invention. It must be distinctly noted that the depth of casing as shown through the line of section 4—4 may be made to extend to the surface of the water above, so as to include the vessel's full area through mid-section 2—2. On the contrary, it might not be necessary to include but a portion of said section 2—2 on account of the "lift" (rise) of the vessel as it moves onward through the water. For example, a steamship of forty-foot beam and draught need not necessarily carry a casing over sixteen-foot depth by forty-foot beam and containing parallel systems of propellers, as indicated in cross-sections, Figs. 5 and 6. This feature ("lift" or rise of vessel), cannot be too attentively considered because it is to and on this angular up-pull of propellers that other very vital features depend.

Projection of the horizontal portion of the casing immediately fronting the uppermost propeller need not extend farther forward than a distance equal to the depth of casing through 4—4. It could extend farther, or not so far, without detriment. An inclined portion of the casing is seen to begin at 10, or near where the angular portion meets the horizontal section of casing, extend downwardly and backwardly, and terminate at the forward edge of the opening 12. The purpose of this inclined portion is that the current may be deflected downwardly so as to throw the force of the "swell", that is, its crest, at a given point under the vessel.

The part of the casing immediately enclosing the propellers extends substantially at the same angle as the propeller shaft, or it may be so shaped as to best suit one or more systems of propellers. The casing is formed preferably of ship-plates, built into and onto the hull of the vessel, which in effect strengthens the front of the vessel and is less difficult to build than long tapering bows, because it conforms nearer to true mechanical shapes. Its construction is there-

fore left to the ship builder. The beginning of the casing commences at 13 by projecting the plates at a point approximately midship of the vessel.

5 By reference to Fig. 1 and considering a given shaped tubular casing lying at an angle of 30 degrees, it will be seen that practically no part, or very little, of the bow is left for resistance. It should also be 10 noted that the angle of the propeller shaft need not be identical with that of the casing; it may be slightly more or less elevated. For example, it might be 31 degrees, while the mean angle of the casing remains at 15 30 degrees. This would tend more directly to throw water from the uppermost inside of the casing, which would be the side of resistance, were the water not drawn from it. But in point of fact, I consider an angle 20 of 30 degrees best for better results and that the angle of shaft and casing should be the same.

Referring to diagram, Fig. 7, it will be observed that line *m*, drawn diagonally at 25 30 degrees across the casing, is exactly twice as long as the line *n*, drawn at a right-angle to the casing; consequently, any reduction in the diameter or size of current removes the water from the bow of the ship a distance twice that of the reduction of the radius. Attention must be called to the fact that, as the ship's line of travel must always be at an angle to the line of current from the 30 propellers, it is evident that any reduction 35 of current makes resistance in front of its line of travel impossible; propellers being the moving force, the ship would have to perform the anomaly of doubling its speed on them and of running ahead of its driving 40 power before it could run into any resistance from the water in front. Any slight contraction of the diameter of the current, for this reason, makes it easier to avoid resistance.

45 My invention being a principle, or combination of principles, intended to avoid resistance at front as one of its main features, Fig. 7 is given only for purposes of illustration. As the mechanism and machinery is extremely simple in this device and its principles are practically everything, it is necessary to explain these at some length. The continuous spiral screw, shown in Fig. 7, would in almost every instance 50 be preferably of two or more vanes, their pitch ratio increasing from upper to lower end, because in every form of propeller used their vanes should impinge steadily on the current as it passes. Their diameters, or 55 length of blades, may be decreased, as pitch increases, to advantage, because the current here is smaller than above, having been contracted by the action of the propellers above. 60 Where a propeller of continuous spiral vanes 65 is used, it is suggested that they be secured

to the shaft without a hub; they may be conveniently formed of sheet-metal plates secured to the shaft.

All propellers other than continuous spiral screws may be so made as to be adjustable 70 to different positions on the shaft. This is desirable so that experience may be gained for best results, practically without cost. They should, however, be so located as to impinge on and assist in keeping the diameter of the current contracted, or in further contracting it, until it leaves the lowest propeller. The propellers acting to draw the water from the sides of a casing into 75 the current, tends to create a film of dead water outside of the current, and at high speed of the propellers is likely to create somewhat of a void or a partial vacuum. A high degree of void is not desirable because the outside water would rush in with 80 tremendous force and thus create a resistance, something this invention is trying to avoid. The higher the speed of the propeller, the greater the suction from the walls 85 of the casing. To control the degree of void, adjacent the walls, a counter-balanced air-valve 15 is provided, preferably in the upper wall of the casing, said valve being connected to a pivoted scale-beam on which 90 is mounted a slidale weight to regulate the opening and closing of the valve, depending on the amount of suction created by the 95 propellers.

In Fig. 2 is shown the preferred form of 100 the bottom of the vessel from the discharge-end of the casing 1 to the extreme end of the stern when a double series of propellers is used, the object of this particular shape being to more effectually utilize the 105 uplifting force of current from the propellers.

Theory of operation.

Figuratively, it may be said the purposes and objects of my invention are attained by 110 taking a propeller or propellers from the stern of a vessel and placing same in a tubular casing of certain preferred angle at the bow of the vessel, as indicated in Fig. 1. The greatest objects of this are to avoid 115 resistance of the water in front, and to prevent the loss of power, as happens when the propellers are located at the stern.

Resistance of water to all moving bodies, 120 including ships, power or sail, is a natural law and will always resist all bodies coming in direct contact with it at a rate which increases in proportion as the square of its rate of speed increases. To double the speed with a given resistance requires that the power must be increased four times, and so on up, still more prodigious at each successive attempt for increased speed. I avoid 125 this resistance at the front, or bow, as follows:

Power being applied which sets the pro- 130

propellers in motion, they in turn set in motion a current as indicated by the arrows. As a section of tubular casing extends forward and parallel with the surface of the water, 5 the current created comes only in contact with the bevelled front edge 16 of the casing. An atmospheric pressure of fifteen pounds per square inch, to which must be added the weight of the water above, causes the water 10 to enter the tubular casing in a current to the propellers when same are in rapid motion, precisely on the same principle and in the same manner that water flows through any tube or pipe towards a vacuum. The 15 degree of contraction of the current will, of course, depend on the speed and pitch of the propellers. If the speed of the propellers were increased to such speed as to equal the effect of a perfect vacuum, the current 20 flowing to them could no longer be further contracted because at such speed, full atmospheric and water pressure would be attained. But contraction under such conditions would be very great, far more than 25 necessary to avoid frontal resistance because it is, in fact, the ship's speed toward the water and not the speed of the water to the ship which could cause resistance in this particular case. The speed of the vessel 30 being always dependent on the pitch and revolutions of the propellers, the vessel could in no instance run into resistance.

It is evident that as the propellers first act 35 on the water, diverting its course, contracting the size of the current entering the casing, and by impinging on same exerts a force for pulling the vessel forward, it can in no wise resist same at bow. It is not too much to say that resistance under this arrangement is impossible at a ratio even approximating the ratio of the square of the 40 rate of speed, because clearance and contraction of the current ever becomes greater as speed increases. I do not affirm, however, that absolutely all resistance is avoided, but only that it is so relieved that it cannot 45 resist at a ratio proportioned to the square of the rate of speed.

Another feature necessarily flowing from 50 this is a contracted current projected at an angle into dead water beneath the vessel, where it will expand again in a swell in the vessel's wake. There appears to be certain advantages in this, one of which is a negative one, in that it does not throw a whirling torrent from the stern as is the case in present practice. The magnitude and intensity 55 of this swell I am not able to estimate, still less to describe or to represent by art, but that it is tremendous, even with small vessels, cannot be doubted. It is seen in the wake of all self-propelled vessels.

A still further feature is an upward lifting 60 force by which the vessel may be made to ride higher out of the water. This, of

course, means less resistance per cargo. If I am told that all propellers may be set at a lifting angle at stern, I answer that all such lifts tilt the vessel forward to sink it deeper toward the bow. This swell referred to 70 under the vessel acts in conjunction with propellers in their lift of the vessel.

Referring to Fig. 8, the very opposite takes place. If seen as it really is, instead of as indicated by arrows, we would see a current beneath the vessel, beginning at its greatest mid-section, increasing in volume and intensity as it nears the stern, and becoming a rolling, twisting torrent beyond the propeller. But only a percentage of this is seen because it takes place beneath the surface. We may often see water lowered at the stern, where it were best it were highest, due to the action of the propeller beneath. This propeller is busy withdrawing atmospheric and water pressure from the vessel's stern, pressure which ought to be the vessel's greatest driving power. Here again, as may be seen as indicated by arrows in Fig. 8, the sides of the propeller blades 85 next the vessel are running away from the water, a fact detrimental to propulsion in this instance because it draws pressure away from the stern of the boat.

A properly shaped vessel may and should 90 have considerable lift. But lift must always depend on speed; the greater the speed, the higher the boat rides towards the surface. This is especially true of sail ships 95 because they have no propeller at the stern undermining and drawing water from their bottoms; increased ratio of resistance at the bow is their only difficulty. To illustrate by figures, we will suppose each vessel indicated by Figs. 1 and 8 to be 16-foot 100 draught and contain 300 square feet across their greatest immersed section. Each would then have over 950,000 pounds of atmospheric and water pressure on each of the opposite sides of this section; that is, at 105 their bows and sterns the pressure at the bow and at the stern pressing in opposite directions in such exact poise that it may be said a child could move them so far as 110 resistance of friction is concerned. If we 115 next suppose each vessel with no driving power, but with no resistance in front and still having its atmospheric and water pressure at stern, each would glide forward at an incredible speed, assuming them to maintain their levels and with their sloping bottoms forming inclined planes down which 120 they glide. Now suppose the resistance to be removed at the bow by a 500 H. P. engine driving propellers in the casing, as in Fig. 1; then the principles I propose to use in 125 steamship propulsion will be clearly seen.

With the resistance removed by this engine, which is also exerting a pulling and a lifting force, the water and atmospheric pres- 130

sure behind (over 900,000 pounds in the size ship mentioned, if sunk to its natural level), and the lifted weight of the vessel will force the vessel down a continuous incline 5 toward the space constantly being cleared at the bow, these being, in a nut-shell, the principles on which I base my invention, the great object sought by means of this device being to so relieve self-propelled ships from 10 all resistance except friction that they may travel free in response to the application of power on the principle of a fly-wheel.

Any body, once in full motion, requires no further force to maintain its acquired 15 motion than that necessary to overcome friction and any air or other resistance it may encounter. This is equally true of a battleship and of a train, but the friction on the train is a great many times greater than on 20 the battleship. Extra power necessary to be expended up-grade is compensated for, theoretically, down-grade.

But my illustration above of the 500 H. P. and how its force is expended is apt to be 25 construed to mean that I claim for my device (or principles of propulsion) not only this whole 500 H. P., which is the full force of the supposed engine, but also an extra force of over 950,000 pounds pressure at the 30 stern, plus the lifted weight of the vessel down the incline of the keel. This would be claiming something for nothing, the equivalent of perpetual motion, or a little better, and would, of course, be absurd. On the 35 contrary, I claim for my ship not one iota more power than is expended by its engines, but what I do claim is that by this arrangement the resistance of the water is relieved from the bow of the ship by the contracting 40 force of the propellers; that the ship is lifted in the water by the lifting force of the propellers, thus further reducing frontal resistance; that the power exerted by the engine in removing resistance at the bow is 45 compensated for by the pressure of the water and air at the stern; and that the engine power exerted in raising the ship is compensated for by the pressure of the lifted weight down the incline of the keel; and 50 that all the power of the engines that is not devoted either to removing resistance in front or to lifting the vessel higher in the water is used as a direct forward pulling 55 force.

The end of the casing in front of the propellers has already been mentioned, but more should be said of its objects in connection with the propellers in keeping back an excess of water, that is, a body in excess of 60 that in the actual path of the ship. At the same time, it largely prevents that whirling motion common to all propellers at the stern, and, by preventing this whirling motion, the propellers impinge more forcibly 65 on the water. Thin steel ribs 14 may also

in some instances be placed to advantage and without obstruction to the current.

I now ask that attention be turned to Figs. 1 and 8, and that they be considered with reference to each other. I think it fair 70 to say that the water is not resisting in the path of Fig. 1, as it is in that of Fig. 8; that a whirling torrent is no longer being thrown from the stern of Fig. 1 as it is from Fig. 8; that no matter what minor resistance there may still be with the Fig. 1 construction, that resistance cannot increase at a ratio proportionate to the square of the 75 rate of speed of the ship, as it would do with the Fig. 8 type, to attain all of which I claim 80 not a single principle or law of nature has been offended. I also think my claim well founded that a system of several propellers mounted on a single shaft within a casing 85 excluding all water except that to be removed, as and for purposes described, is more effective as a pulling force than one at the stern can be as a driving one, equal power being applied to both.

Heretofore I have referred to my invention as it relates to avoiding resistance at the bow, this to prevent confusion. The principles on which this resistance increases according to the square of the rate of speed 90 is well understood. It is not so well understood that a still greater expenditure of power is unnecessarily required at the stern, because of the great loss occurring there, and that because of this loss the power necessary 95 to propel a ship must be multiplied by the "cube" of its rate of speed, instead of by the "square" necessitated by the resistance in front. As this is a mechanical loss, not running according to philosophical principles, the amount of it varies according to 100 practical considerations so that in a few instances it has been found to be a little less, but generally the "cube" is correct, which is to say that in increasing speed 105 from a rate of ten miles to thirty miles an hour, power must be increased twenty-seven times, because the rate of increase of speed is three times, and the cube of three is twenty-seven. Calling attention, then, to the fact 110 that three times three is nine and nine times three is twenty-seven, brings me to the last and most important feature of my invention, which consists in leaving off propellers at the stern and enclosing them in a suitable 115 casing at the front, as herein described and illustrated. Observing that lost force at the stern greatly exceeds resistance at the bow in all high speeds in the present practice, I consider the objects sought and the principles employed to attain them in my 120 invention have been sufficiently explained.

In the example just cited, it was shown how a loss of power at the stern, as seen in Fig. 8, could exceed resistance in front in 125 proportion of two to one. Had the rate 130

been carried higher, say from 10 miles an hour to 40 miles, the proportion would have been as three to one, and so on up with each increase of speed. It is the avoidance 5 of loss at the stern and resistance in front which I claim to attain by my invention, as shown in Fig. 1 of the accompanying drawings. To explain clearly the division of unnecessary power between this resistance in 10 front and this loss at the stern in present methods of propulsion requires one further illustration. Say a ship is traveling at a rate of ten miles an hour with an expenditure of 1000 H. P., and it is desired to increase its speed from ten to 40 miles, or 15 four times. First, its power must be multiplied by the square of its rate of speed to take care of the increased resistance, i. e., four times four times 1000 H. P., or 16,000 20 H. P., which would be the actual resistance of the water in front. But, as actual multiplication of power must be by the cube of the rate of increased speed, we must multiply again, and we say 16,000 H. P. four 25 times is 64,000 H. P. Subtracting 16,000 H. P. (the power required by increased frontal resistance) from 64,000 H. P. leaves 48,000 H. P., which must be credited to the loss by the propeller at the stern, because we 30 have already allowed full legal resistance of 16,000 H. P.; therefore, any manner by which the propeller is left off or removed from the stern, without any corresponding 35 disadvantage, would in the above case save this excessive loss of power. All this has been said to emphasize the important feature of getting propellers away from the stern, and it should be observed that the 40 methods herein employed are those of principles rather than of mechanism.

Now I claim that a system of propellers as illustrated in Fig. 1 will far exceed in 45 effective propelling power any which may be placed at the stern, equal power applied in both cases. It follows inevitably that this great loss of power at the stern, which added to resistance in front mounts up to a multiplication of power by the cube of the rate 50 of increase of speed, would be saved by placing propellers as indicated in Fig. 1.

My main objects, therefore, are to avoid 55 these great difficulties to ship propulsion in such a manner as to leave only friction to be overcome, and I aver that friction is but negligible compared to the one great difficulty of frontal resistance. Great ocean steamers carrying three and four huge steel masts with great spread of sail, stand out as witnesses to the errors in our present methods of propulsion to which I have called attention. They testify that added speed by further cumulation of power applied to propellers at the stern has reached the utmost 60 limit consistent with reason and economy. Applied power being superior to sails, why

use sails at all? Why not more power? Because the additional power gained by the use of sails is all utilized in overcoming resistance in front, while that applied to the propellers would be mainly kicked away at 70 the stern.

Among minor advantages incidental to the principles as applied to the above proposed new method of boat propulsion, should be mentioned the extra lift caused by increase of speed—increased speed meaning higher lift and higher lift meaning increased speed. Among various other advantages, one other is especially worthy of mention. I allude to that feature whereby the vessel 80 is held more firmly from rolling by the angular uppull of the propellers in front.

What I claim is:

1. In a marine vessel, a hull having a bow front wall inclining downwardly and rearwardly and merging gradually with the bottom of the hull, a casing on the front wall of the hull forming a chamber having the width of the vessel, said chamber being open at its front end and at its lower rear end, 90 and an inclined propelling means located within said chamber and adapted to drive the water therein downwardly and rearwardly, as and for the purposes set forth.

2. In a marine vessel, a hull having a bow front-wall inclining downwardly and rearwardly to the bottom of the hull at a point approximately midship thereof, a casing extended from said bow front-wall toward the front end of the vessel, said casing throughout its length being approximately equal in width to the beam of the vessel and having an open rear end and also a front end wholly open, whereby only its front edge offers a resistance against the water when the vessel 100 is moving forwardly, and a propeller means located within said casing and inclined downwardly and rearwardly substantially parallel with said bow front-wall.

3. In a marine vessel, a hull having a bow front-wall inclining downwardly and rearwardly to the bottom of the hull at a point approximately midship thereof, a casing having a bevelled front edge extended from said bow front-wall to the front end of the vessel, said casing throughout its length being approximately equal in width to the beam of the vessel and having an open rear end and also a front end wholly open, whereby only its front edge offers a resistance against the water when the vessel 110 is moving forwardly, and a propeller means located within said casing and inclined downwardly and rearwardly substantially parallel with said bow front-wall.

4. In a marine vessel, a hull having a bow front-wall inclining downwardly and rearwardly to the bottom of the hull at a point approximately midship thereof, a casing extended from said bow front-wall toward the 120

- front end of the vessel, said casing throughout its length being approximately equal in width to the beam of the vessel and formed with a downwardly and rearwardly inclined 5 wall portion at its lower end which is substantially parallel with the bow front-wall and having an open rear end and also a front end wholly open, whereby only its front edge offers a resistance against the water when 10 the vessel is moving forwardly, and a propelling means located within said casing and inclined downwardly and rearwardly substantially parallel with said bow front-wall.
- 15 5. In a marine vessel, a hull having a bow front-wall inclining downwardly and rearwardly to the bottom of the hull at a point approximately midship thereof, a casing extended from said bow front-wall toward the 20 front end of the vessel, said casing throughout its length being approximately equal in width to the beam of the vessel and having an open rear end and also a front end wholly open, whereby only its front edge 25 offers a resistance against the water when the vessel is moving forwardly, and a propelling means located within said casing and inclined downwardly and rearwardly substantially parallel with said bow front-wall,
- 30 said propelling means embodying a plurality of propellers in alinement with each other and of less diameter than the inside of the casing to provide a substantial clearance space between the peripheries of the propellers and the walls 35 of the casing.
6. In a marine vessel, a hull having a bow front-wall inclining downwardly and rearwardly to the bottom of the hull at a point approximately midship thereof, a casing extended from said bow front-wall toward the 40 front end of the vessel, said casing throughout its length being approximately equal in width to the beam of the vessel and having an open rear end and also a front end wholly 45 open, whereby only its front edge offers a resistance against the water when the vessel is moving forwardly, and a propelling means located within said casing and inclined downwardly and rearwardly substantially parallel with said bow front-wall, said propelling means embodying a plurality of propellers of decreasing diameter toward the lower end of the propeller-shaft and in alinement with each other and of less diameter 50 than the inside of the casing to provide a substantial clearance space between the peripheries of the propellers and the walls of the casing.
7. In a marine vessel, a hull having a bow front-wall inclining downwardly and rearwardly to the bottom of the hull at a point approximately midship thereof, a forecastle room located in a plane above said bow front-wall and in front of the same, a casing 60 extended from the bow front-wall toward the front end of the vessel, said casing throughout its length being approximately equal in width to said forecastle room and having an open rear end and also a front end wholly open, and a propelling means arranged in parallel relation to the bow front-wall and embodying a shaft extended into the said forecastle room, a thrust bearing for the upper end of said shaft secured against the front-wall of the forecastle 65 room, and a plurality of propellers mounted on said shaft inside of said casing.
8. In a marine vessel, a hull having a bow front-wall inclining downwardly and rearwardly, a forecastle room in a plane above said front-wall and extended beyond the same, a casing in front of said front-wall and forming a chamber underlying the forecastle room, a propelling means located in said casing and lying approximately parallel to the front-wall, said casing being 70 equal in width to the beam of the vessel and being wholly open at both ends, and also provided with longitudinal ribs on its interior face of its walls to prevent the whirl of 75 the water flowing through the same.
9. In a marine vessel, a hull having a bow front-wall inclining downwardly and rearwardly, a forecastle room in a plane above said front-wall and extended beyond the same, a casing in front of said front-wall and forming a chamber underlying the forecastle room, a propelling means located in said casing and lying approximately parallel to the front-wall, said casing being 80 equal in width to the beam of the vessel and being wholly open at both ends, said front-wall being curved at its lower end to merge 85 gradually with the bottom-wall of the hull, and said bottom-wall being formed with a longitudinal groove to effectively utilize the 90 uplifting force of the current formed by the propellers.
- In testimony whereof I hereunto affix my signature.

BENJAMIN FRANKLIN WRIGHT.
